SHUFFLEBOARD CUE

Asa Cassidy, Tampa, Fla.

Application April 6, 1939, Serial No. 266,353

4 Claims. (Cl. 273—129)

The invention relates to a cue construction and more especially to a shuffleboard cue.

The primary object of the invention is the provision of a cue of this character, wherein the same is formed with a substantially arrowhead-shaped head adapted to rest directly upon the game piece for the playing of the game of shuffleboard and carries downwardly directed portions at the rear of the game piece so that it can be set in motion in the playing of the game.

Another object of the invention is the provision of a cue of this character, wherein the construction thereof is novel in its entirety and its handle is pivotally supported relative to a head so as to have limited swing without interfering with the sending of the game piece in the use of the cue for the playing of shuffleboard.

A further object of the invention is the provision of a cue of this character, which is simple in its construction, thoroughly reliable and effective in operation, readily and easily handled, light in weight yet strong, durable, and inexpensive to manufacture.

With these and other objects in view, the invention consists in the features of construction, combination and arrangement of parts as will be hereinafter more fully described, illustrated in the accompanying drawing, which discloses the preferred and modified forms of embodiment of the invention and pointed out in the claims hereunto appended.

In the accompanying drawing:

Figure 1 is a perspective view of a game piece showing the cue constructed in accordance with the invention in applied position.

Figure 2 is a side elevation of the game piece showing the cue in vertical section.

Figure 3 is a rear elevation partly in section.

Figure 4 is a top plan view of a modified form of cue.

Similar reference characters indicate corresponding parts throughout the several views in the drawing.

Referring to the drawing in detail, particularly Figures 1 to 3, inclusive, A designates a game piece, which, as is conventional, is of disk form for the playing of the game of shuffleboard and such game piece or playing piece is sent in its course in the playing of the game by a cue constituting the present invention and comprises a handle, a portion thereof being indicated at 10, and is attached to a head, generally denoted at B.

The head B is formed from a single blank of cast or sheet metal, its body 11 being of arrowhead formation, while struck upwardly from this

body 11 at the longitudinal center thereof is a forwardly inclined rib 12, which at the inner side thereof constitutes a channel or groove 13 for the reception of the end of the handle 10. This end of the handle is diagonally cut to form a beveled extremity 14. The rib 12 is carried rearwardly beyond the body and at opposite sides thereof are cheeks or ears 15, these accommodating a cross pivot 16, which is passed transversely through the handle 10. The pivot 16 is arranged so as to give a limited vertical swing to the handle 10 when pocketed within the groove or channel 13.

The body 11 at the rear portion thereof is formed with laterally directed rearwardly divergent extensions or wings 17, these being turned downwardly at the ends thereof to provide pusher abutments or jaws 18 for engaging the peripheral portion of the game or play piece A when the head B is superimposed thereon to enable the said game or playing piece to be sent in its course in the playing of the game of shuffleboard.

The body 11 at the longitudinal median thereof is formed with a forwardly directed substantially arrowhead-shaped toe 19, which has contact with the upper face of the game or playing piece A when the head is engaged therewith in the use of the cue for the sending of said game or play piece in the playing of shuffleboard. The beveled extremity 14 of the handle 10 at all times 30 is out of contact with the game or playing piece A on application of the head thereto and affords a clearance therebetween for limited swing of the handle 10 on the pivot 16 in the use of the cue.

In Figure 4 of the drawing there is shown a slight modification wherein a single length of wire is bent into an arrowhead-shaped head 20 having the lateral rearwardly divergent wing extension 21 and toe 22, respectively, while this frame 20 has bent therefrom the rearwardly directed and forwardly inclined spaced parallel arms 23 for attaching a cross pivot 24 thereto, the said pivot being passed transversely through the handle of the cue, a portion of the handle being indicated at 25, and in this manner the said handle is pivotally connected to the head.

Bent from the wings 21 are the downturned pusher jaws 26, which function correspondingly to the jaws 18 hereinbefore set forth.

In Figures 1 to 4 the preferred and modified forms of cue are shown in applied position to the game or play pieces for the playing of the game of shuffleboard, the toe 19 or 22 being in resting position upon the top of the game or play piece while the jaws 18 or 26 peripherally engage the

said game or play piece for convenient sending of the latter in its course when playing the game of shuffleboard.

What is claimed is:

- 5 1. A cue of the character described comprising an arrowhead-shaped head having pusher jaws rearwardly and laterally disposed of its transverse and longitudinal medians, a toe forwardly of the head at the longitudinal median thereof, and a forwardly inclined handle fitted with the head and having limited vertical swing.
- 10 2. A cue of the character described comprising an arrowhead-shaped head having pusher jaws rearwardly and laterally disposed of its transverse and longitudinal medians, a toe forwardly of the head at the longitudinal median thereof, a forwardly inclined handle fitted with the head and having limited vertical swing, and means swingingly connecting the handle with the head.
- 15 3. A cue of the character described comprising an arrowhead-shaped head having pusher jaws rearwardly and laterally disposed of its transverse and longitudinal medians, a toe forwardly of the head at the longitudinal median thereof,
- 20

a forwardly inclined handle fitted with the head and having limited vertical swing, means swingingly connecting the handle with the head, and a rib struck upwardly from the head at its longitudinal median and partially accommodating the 5 handle.

4. A cue for a play disc of a shuffleboard game, comprising a substantially arrowhead-shaped body forming forwardly and rearwardly and laterally disposed extensions arranged at the same 10 level with respect to each other for contact with the play disc, a pointed toe formed at the forward extension, down-turned abutments at the ends of said rearward and lateral extensions for engaging the periphery of said disc at a point 15 considerably rearwardly of the toe, a rib struck upwardly from the said body at the longitudinal median thereof and inclined forwardly for receiving a handle, and a handle pivotally mounted in said rib and having a beveled inner end for 20 contact with the disc to limit the swing of said handle in a vertical direction.

ASA CASSIDY.
